SPRAY GUN

John F. Siefen, Detroit, Mich.

Application May 31, 1956, Serial No. 588,475

8 Claims (Cl. 299—86)

My invention relates to a new and useful improvement 15 in a spray gun for spraying buffing compounds, paints and/or like material in an atomized state.

Spray guns have been developed which are commonly referred to as being automatically operated. These automatic spray guns are of two general classes, but in both 20 classes mechanical or electrical air controls are used which are set at an external point generally several feet from the spray gun. This is a disadvantage as it requires a certain length of time, from a fraction of a second to two seconds, for the air to travel from the 25 external control to the outlet nozzle of the spray gun, when starting to spray, and, also, it requires a certain length of time to exhaust the air to the stop-off point when stopping a spraying operation. These types of 30 guns are generally recognized as having certain disadvantages.

One type of the aforementioned spray guns requires two air hoses to be led to the spray gun. One of these air hoses furnishes air at a normal high pressure to move a piston which opens an internal valve so as to permit air from a second air hose to be delivered through passages in the body to the air cap. The second air hose is used for delivering atomizing air to atomize or break 35 into small particles the material being sprayed. The piston, after traveling a short distance opens a needle valve, 40 allowing the sprayed material to pass through the fluid tip.

A second broad classification of spray guns on the market today uses one air hose so that the supply of air, regulated at an external valve, moves a piston or diaphragm to open the needle valve. Through passages in the body of the spray gun this same supply of air is used to atomize the spray material. This type of gun generally has a spattering of the spray at the beginning and end of each operation which is especially noticeable at 45 the end of the operation. This is due to the needle valve opening before normal atomizing air pressure has been built up at the air cap and, on closing, the atomization pressure at the cap drops before the needle closes.

The present invention has as its object the avoidance 50 of these difficulties and the provision of a spray gun so arranged and constructed so that no external air valve to control the air flow is required, as the air control valve is made as a part of the gun itself.

Another object of the invention is the provision of a spray gun of this class having an air control valve adapted to provide substantially instantaneous opening and closing of the valve at the beginning and end of the operation.

Another object of the invention is the provision of a spray gun of this type wherein the air under proper pressure for atomization is always present in the gun, so that the disadvantages referred to as to the sprayed material are avoided.

Another object of the invention is the provision of a spray gun which will be simple in structure, economical of manufacture, highly efficient in use and light and compact.

2

Other objects will appear hereinafter.

It is recognized that various modifications and changes may be made in the details of the structure illustrated without departing from the invention, and, it is intended that the present disclosure shall be considered to be but the preferred embodiment.

Forming a part of this application are drawings, in which,

Fig. 1 is a side elevational view of the invention;

Fig. 2 is an end elevational view of the invention;

Fig. 3 is a longitudinal central sectional view of the invention showing the control parts in one position;

Fig. 4 is a view similar to Fig. 3 showing the control parts in another position;

Fig. 5 is a fragmentary sectional view taken on line 5—5 of Fig. 3.

In the drawings I have indicated the spray gun as comprising a body 15 having a chamber 16 at the forward end thereof communicating through the passage 17 with a fitting 18 to which a conduit may be attached for delivery of the spray fluid into the chamber 16. Threaded into the end of the body is a nozzle 19 having an outlet opening 20 and hollow to provide a compartment 21 for reception of spray fluid. A needle valve 22 is adapted to engage at its end and close the outlet opening 20.

Secured on the end of the body 15 by means of a collar 24 is an air cap 23 having passages 25 formed therein communicating with the outlet passages 26 and also forming passages 27 downwardly through the grooves 28 formed on the conical end 29 of the nozzle 19, and outwardly through the annular passage 20b, around the outlet sleeve or terminus 20a of the nozzle 19. The air under pressure emits through passage 20b to atomize the fluid which emits from opening 20 and emits through passages 26 to form or shape this atomized fluid stream.

A nipple 27 is adapted for being connected to an air hose so that the air under pressure may be delivered into the internal air passages 28 into the cylinder 29 at one side of the piston 30. This piston 30 is provided with a hub 31 on which is threaded a retainer 32 which is adapted to serve as a piston guide and which cooperates with the end face of the piston 30 to retain the sealing ring 33 in engagement with the bottom of the cylinder 29, so as to close communication of the space 34, which surrounds the retainer 32 with the cylinder 29. The piston 30 is provided with a bleed passage 30a for equalizing air pressure on opposite sides of piston 30 in cylinder 29.

The piston 30 is provided on its periphery with the sealing ring 34a, as for example, a sealing ring of the O type. Secured on the opposite end of the body 15 by means of the collar 35 is the support or retainer 36 which is threaded onto a fitting 37 which is fixedly mounted on the solenoid housing 38.

The cylinder 29 communicates with the atmosphere by the following described conduit means. A chamber 39 is formed in the retainer 36 and communicates through the passage 40 with the compartment 41. This compartment 41 is adapted to communicate through the passages 42 and 43 with the atmosphere.

A valve head 44 is projectable into the chamber 41 and this valve head carries at its end a composition disc valve 45 which serves to engage over the passage 42 and close the same, so that the chamber 41 is then no longer in communication with the atmosphere. A bead 46 on the valve head 44 engages one end of the coil spring 47, the other end of which engages an annular seat in the fitting 37. This valve head 44 is connected to the core 48 of the solenoid coil 49 which may be electrically connected to a source of energy by means of the cable 50.

Formed in the piston 30 is a recess 51 in which is

3
slidably mounted a pair of spaced apart integral annular flanges 52 and 53, carried by the stem of the needle valve 22. A sealing ring 54, preferably one of the O type, is positioned between said flanges 52 and 53.

A coil spring 55 engages at one end the flange 53 and at its other end the bottom of the chamber or compartment 39. Embracing this coil spring 55 is a coil spring 56 which engages at one end the bottom of the compartment or chamber 39 and at its opposite end in a recess 57 formed in the face of the piston 30.

The space 34 surrounding the retainer 32 is in communication with a plurality of passages 58 formed in the body 15. These passages 58 communicate with the space 59 which is between the end of the body 15 and the air cap 23.

In use the spray fluid would always be under pressure, so that in the chamber 21 spray fluid would be ready for emission through the outlet opening 20 upon opening of the needle valve 22. This needle valve 22 passes through a packing 60 which may be packed by the gland 61 which is accessible through the opening 62 formed in the body 15. The packing 60 functions as a spray fluid seal to prevent leakage from the chamber 16. This gland is provided with a head 63 for the reception of a suitable wrench. As shown in Fig. 3, the needle valve 22 also projects through a sealing ring 64, preferably of the O type. The sealing ring 64 is seated around the needle 22 in a recess in the face of a collar 64a which is mounted in the recess 64b in the body 15. The sealing ring 64 is operatively retained in the collar 64a by means of the collar 64c which is threadably mounted in the body 15. The sealing ring 64 functions as an air seal to prevent air leakage around the needle valve 22 from the chamber 34.

When the spray gun is set up for use, compressed air under pressure will flow through the fitting 27 and the passage 28 into the cylinder 29, at the right side of the piston 30, as viewed in Figs. 3 and 4, and through passage 30a in the piston 30 to that portion of cylinder 29 to the left of piston 30. As communication of the cylinder 29 at the left of piston 30 with the atmosphere through passages 42 and 43 is closed no movement of the piston to the left takes place. Bleed passage 30a is formed through piston 30 so that the air pressure on both sides of the piston 30 is equalized.

Consequently, the spring 56 will retain the piston 30 in a closed or "at rest" position as shown in Fig. 3, and, the pressure of the spring 55 will retain the needle valve 22 in a closed or "at rest" position.

A suitable switch would be interposed in the cable 50 and upon closing of this switch and the energizing of the solenoid 49, the armature 48 would move to the left, as shown in Fig. 4, so that the composition disc valve 45 would move into an opening position relative to the chamber 41 and thus permit communication of the cylinder 29 at the left side of the piston 30 with the atmosphere, through passages 42 and 43. This would unequalize the air pressure on opposite sides of the piston 30 so that said piston would move to the left as shown in Fig. 4, so as to establish communication between the cylinder 29 and the space 34 around the retainer 32. Therefore, the air in the cylinder 29 would pass through the space 34 and through the passages 58 to the passages 59, 73, 74, 25, 26 and 20b. After the piston 30 has moved to the left a short distance it would pick up and move the needle valve 22 to the left. In this movement there would be a lag in said picking up effect, on account of the gap 51, so that the sealing ring 33 would move to an open position before the needle valve 22 moved to open position. This lag would be of very short duration, but, before the spray fluid would issue from the opening 20, atomizing air would be issuing through the passages 20b and 26. Consequently, any fluid emitting through the outlet 20 will be immediately subjected to the air action.

4
In stopping the operation, upon deenergization of the solenoid 49, the core 48 would be moved to the right in response to the spring pressure 47, thus cutting off communication of the cylinder 29 with the atmosphere. The air pressure on opposite sides of the piston 30 would then build up to equal pressures, and the spring 56 would force the piston 30 to the right. At the same time, spring 55 would force the needle valve 22 to the right. After piston 30 and needle valve 22 have moved to the right a distance equal to the travel distance between the open position of the needle valve 22 and the closed position of said needle valve, the delivery of spray fluid would cease. Piston 30 continues moving to the right, on account of gap 51, to its closing position, cutting off communication of cylinder 29 to space 34 by sealing ring 33. Thus, atomizing air would cease to flow through passages 58, 59, 73, 74, 25, 26 and 20b. This time lag on stopping the operation would assure that all spray fluid would atomize, as the spray fluid will cease before atomizing air would cease. The spray gun is now "at rest" or closed position.

In this manner, the various disadvantages and difficulties would, therefore, be overcome and a substantially instantaneously controlled spray would be accomplished.

25 As shown in Figs. 4 and 5, formed through the body is a passage 76 through which may be extended a stud 77 which threads into a stem 78 of a yoke embodying the separated arms 79 and 80 of Fig. 2, which may be drawn together by a suitable screw 81 so that the arms 30 79 and 80 may clamp against a suitable support or rod which may be projected through the opening 82, thus affording a means of mounting the gun in stationary position when desired.

What I claim is:

1. A spray gun of the class described, comprising: 35 a body; an outlet nozzle mounted on one end of said body and having an outlet opening for the emission of liquid therefrom; a cylinder on the opposite end of said body; a retainer mounted on said opposite end of said body and forming a closure for said cylinder and having conduit means communicating said cylinder with the atmosphere; said conduit means including a compartment, a first passage communicating said compartment with said cylinder, and a second passage communicating said compartment with the atmosphere; a valve in said 40 compartment for closing communication between said passages; a piston slidably mounted in said cylinder; a spring in said cylinder normally urging said piston in one direction; an inlet port in said body communicating with said cylinder at one side of said piston for conducting air under pressure thereinto, and moving said piston in the opposite direction against the compression of said spring; an inlet port in said body for conducting liquid under pressure into said body for emission through the outlet opening of the said nozzle; a rod in said body having a needle valve at one end for engaging said nozzle and closing said outlet opening; said rod at its opposite end extending through said piston; and, an enlargement on said rod engageable with said piston, 45 upon movement of said piston against the compression of said spring a slight distance for engaging said needle valve and moving said needle valve to open position.

2. A spray gun of the class described, comprising: a body; an outlet nozzle mounted on one end of said body and having an outlet opening for the emission of liquid therefrom; a cylinder on the opposite end of said body; a retainer mounted on said opposite end of said body and forming a closure for said cylinder and having conduit means communicating said cylinder with the atmosphere; said conduit means including a compartment, a first passage communicating said compartment with said cylinder, and a second passage communicating said compartment with the atmosphere; a valve in said compartment for closing communication between said passages; 50 a piston slidably mounted in said cylinder; a first spring

in said cylinder normally urging said piston in one direction; an inlet port in said body communicating with said cylinder at one side of said piston for conducting air under pressure thereinto, and moving said piston in the opposite direction against the compression of said first spring; an inlet port in said body for conducting liquid under pressure into said body for emission through the outlet opening of the said nozzle; a rod in said body having a needle valve at one end for engaging said nozzle and closing said outlet opening; said rod at its opposite end extending through said piston; an enlargement on said rod engageable with said piston, upon movement of said piston against the compression of said first spring a slight distance for engaging said needle valve and moving said needle valve to open position; and, a second spring extending into said cylinder and engaging at one end said retainer and at the opposite end said enlargement on said rod for normally urging said needle valve into closing position.

3. A spray gun of the class described, comprising: a body; an outlet nozzle mounted on one end of said body and having an outlet opening for the emission of liquid therefrom; a cylinder on the opposite end of said body; a retainer mounted on said opposite end of said body and forming a closure for said cylinder and having conduit means communicating said cylinder with the atmosphere; said conduit means including a compartment, a first passage communicating with said compartment with said cylinder, and a second passage communicating said compartment with the atmosphere; a valve in said compartment for closing communication between said passages; a piston slidably mounted in said cylinder; a first spring in said cylinder normally urging said piston in one direction; an inlet port in said body communicating with said cylinder at one side of said piston for conducting air under pressure thereinto, and moving said piston in the opposite direction against the compression of said first spring, an inlet port in said body for conducting liquid under pressure into said body for emission through the outlet opening of the said nozzle; a rod in said body having a needle valve at one end for engaging said nozzle and closing said outlet opening; said rod at its opposite end extending through said piston; an enlargement on said rod engageable with said piston, upon movement of said piston against the compression of said first spring a slight distance for engaging said needle valve and moving said needle valve to open position; a second spring extending into said cylinder and engaging at one end said retainer and at the opposite end said enlargement on said rod for normally urging said needle valve into closing position; and, said piston having a passage formed therethrough for effecting equalizing of air pressure on opposite sides of said piston.

4. A spray gun of the class described, comprising: a body; an outlet nozzle mounted on one end of said body and having an outlet opening for the emission of liquid therefrom; a cylinder on the opposite end of said body; a retainer mounted on said opposite end of said body and forming a closure for said cylinder and having conduit means communicating said cylinder with the atmosphere; said conduit means including a compartment, a first passage communicating said compartment with said cylinder, and a second passage communicating said compartment with the atmosphere; a valve in said compartment for closing communication between said passages; a piston slidably mounted in said cylinder; a first spring in said cylinder normally urging said piston in one direction; an inlet port in said body communicating with said cylinder at one side of said piston for conducting air under pressure thereinto, and moving said piston in the opposite direction against the compression of said first spring; an inlet port in said body for conducting liquid under pressure into said body for emission through the outlet opening of the said nozzle; a rod in said body

having a needle valve at one end for engaging said nozzle and closing said outlet opening; said rod at its opposite end extending through said piston; an enlargement on said rod engageable with said piston, upon movement of said piston against the compression of said first spring a slight distance for engaging said needle valve and moving said needle valve to open position; a second spring extending into said cylinder and engaging at one end said retainer and at the opposite end said enlargement on said rod for normally urging said needle valve into closing position; said piston having a passage formed therethrough for effecting equalizing of air pressure on opposite sides of said piston; and, a solenoid in said retainer for, upon being energized, opening said first named valve and establishing communication of said cylinder at one side of said piston with the atmosphere.

5. A spray gun of the class described, comprising: a body; an outlet nozzle mounted on one end of said body and having an outlet opening for the emission of liquid therefrom; a cylinder on the opposite end of said body; a retainer mounted on said opposite end of said body and forming a closure for said cylinder and having conduit means communicating said cylinder with the atmosphere; said conduit means including a compartment, a first passage communicating said compartment with said cylinder, and a second passage communicating said compartment with the atmosphere; a valve in said compartment for closing communication between said passages; a piston slidably mounted in said cylinder; a first spring in said cylinder normally urging said piston in one direction; an inlet port in said body communicating with said cylinder at one side of said piston for conducting air under pressure thereinto, and moving said piston in the opposite direction against the compression of said first spring; an inlet port in said body for conducting liquid under pressure into said body for emission through the outlet opening of the said nozzle; a rod in said body having a needle valve at one end for engaging said nozzle and closing said outlet opening; said rod at its opposite end extending through said piston; an enlargement on said rod engageable with said piston, upon movement of said piston against the compression of said first spring a slight distance for engaging said needle valve and moving said needle valve to open position; a second spring extending into said cylinder and engaging at one end said retainer and at the opposite end said enlargement on said rod for normally urging said needle valve into closing position; said piston having a passage formed therethrough for effecting equalizing of air pressure on opposite sides of said piston; a passage in said body for delivering air from said cylinder to and around said nozzle; and, a valve on said piston for controlling communication of said last named passage with said cylinder and movable to open position upon movement of said piston against the compression of the first spring bearing against the same.

6. A spray gun of the class described, comprising: a body; an outlet nozzle mounted on one end of said body and having an outlet opening for the emission of liquid therefrom; a cylinder on the opposite end of said body; a retainer mounted on said opposite end of said body and forming a closure for said cylinder and having conduit means communicating said cylinder with the atmosphere; said conduit means including a compartment, a first passage communicating said compartment with said cylinder, and a second passage communicating said compartment with the atmosphere; a valve in said compartment for closing communication between said passages; a piston slidably mounted in said cylinder; a first spring in said cylinder normally urging said piston in one direction; an inlet port in said body communicating with said cylinder at one side of said piston for conducting air under pressure thereinto, and moving said piston in the opposite direction against the compression of said first spring; an inlet port in said body for conducting liquid under pressure into said body for emission through the outlet open-

ing of the said nozzle; a rod in said body having a needle valve at one end for engaging said nozzle and closing said outlet opening; said rod at its opposite end extending through said piston; a recess in said piston having an inner end face; an enlargement on said opposite end of the rod and being seated in said recess in spaced relation from said recess end face when the needle valve is in the position to close the outlet opening; said enlargement on said rod being engageable with said recess end face in said piston, upon movement of said piston against the compression of said first spring a slight distance for engaging said needle valve and moving said needle valve to open position; a second spring extending into said cylinder and engaging at one end said retainer and at the opposite end said enlargement on said rod for normally urging said needle valve into closing position; said piston having a passage formed therethrough for effecting equalizing of air pressure on opposite sides of said piston; a passage in said body for delivering air from said cylinder to and around said nozzle; and, a valve on said piston for controlling communication of said last named passage with said cylinder and movable to open position upon movement of said piston against the compression of the first spring bearing against the same.

7. A spray gun of the class described, comprising: a body; an outlet nozzle mounted on one end of said body and having an outlet opening for the emission of liquid therefrom; a cylinder on the opposite end of said body; a retainer mounted on said opposite end of said body and forming a closure for said cylinder and having conduit means communicating said cylinder with the atmosphere; said conduit means including a compartment, a first passage communicating said compartment with said cylinder, and a second passage communicating said compartment with the atmosphere; a valve in said compartment for closing communication between said passages; a solenoid connected to said valve for controlling the same and upon being energized, moving said valve to an open position for establishing communication between said passages; a piston slidably mounted in said cylinder; a first spring in said cylinder normally urging said piston in one direction; an inlet port in said body communicating with said cylinder at one side of said piston for conducting air under pressure thereinto, and moving said piston in the opposite direction against the compression of said first spring; an inlet port in said body for conducting liquid under pressure into said body for emission through the outlet opening of the said nozzle; a rod in said body having a needle valve at one end for engaging said nozzle and closing said outlet opening; said rod at its opposite end extending through said piston; an enlargement on said rod engageable with said piston, upon movement of said piston against the compression of said first spring a slight distance for engaging said needle valve and moving said needle valve to open position; a second spring extending into said cylinder and engaging at one end said retainer and at the opposite end said enlargement on said rod for normally urging said needle valve into closing position; said piston having a passage formed therethrough for effecting equalizing of air pressure on opposite sides of said piston; a nozzle cap mounted on said body and embracing said outlet nozzle and having air passages formed therein for discharging air outwardly around said outlet nozzle in the path of flow of liquid passing through said outlet nozzle; a passage in said body for delivering air from said cylinder to the passages in said nozzle cap; and, a valve on said piston for controlling communication of said passage in said body with said cylinder and movable to open position upon movement of said piston against the compression of the first spring bearing against the same.

5 around said outlet nozzle in the path of flow of liquid passing through said outlet nozzle; a passage in said body for delivering air from said cylinder to the passages in said nozzle cap; and, a valve on said piston for controlling communication of said passage in said body with said cylinder and movable to open position upon movement of said piston against the compression of the first spring bearing against the same.

8. A spray gun of the class described, comprising: a body; an outlet nozzle mounted on one end of said body and having an outlet opening for the emission of liquid therefrom; a cylinder on the opposite end of said body; a retainer mounted on said opposite end of said body and forming a closure for said cylinder and having conduit means communicating said cylinder with the atmosphere; said conduit means including a compartment, a first passage communicating said compartment with said cylinder, and a second passage communicating said compartment with the atmosphere; a valve in said compartment for closing communication between said passages; a solenoid connected to said valve for controlling the same and upon being energized, moving said valve to an open position for establishing communication between said passages; a piston slidably mounted in said cylinder; a first spring in said cylinder normally urging said piston in one direction; an inlet port in said body communicating with said cylinder at one side of said piston for conducting air under pressure thereinto, and moving said piston in the opposite direction against the compression of said first spring; an inlet port in said body for conducting liquid under pressure into said body for emission through the outlet opening of the said nozzle; a rod in said body having a needle valve at one end for engaging said nozzle and closing said outlet opening; said rod at its opposite end extending through said piston; a recess in said piston having an inner end face; an enlargement on said opposite end of the rod and being seated in said recess in spaced relation from said recess end face when the needle valve is in the position to close the outlet opening; said enlargement on said rod being engageable with said recess end face in said piston, upon movement of said piston against the compression of said first spring a slight distance for engaging said needle valve and moving said needle valve to open position; a second spring extending into said cylinder and engaging at one end said retainer and at the opposite end said enlargement on said rod for normally urging said needle valve into closing position; said piston having a passage formed therethrough for effecting equalizing of air pressure on opposite sides of said piston; a nozzle cap mounted on said body and embracing said outlet nozzle and having air passages formed therein for discharging air outwardly around said outlet nozzle in the path of flow of liquid passing through said outlet nozzle; a passage in said body for delivering air from said cylinder to the passages in said nozzle cap; and, a valve on said piston for controlling communication of said passage in said body with said cylinder and movable to open position upon movement of said piston against the compression of the first spring bearing against the same.
